UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

DRAW-BAR YOKE.

1,188,434.

Specification of Letters Patent. Patented June 27, 1916.

Application filed July 6, 1915. Serial No. 38,249.

To all whom it may concern:

Be it known that I, WILLIAM D. FORSYTH, a citizen of the United States, and a resident of the city of Youngstown, in the 5 county of Mahoning and State of Ohio, have invented a new and useful Improvement in Draw-Bar Yokes, of which the following is a specification.

This invention relates to draft gear casings or yokes for connecting the draw bar and the springs and followers of the draft gear of railway cars, and it consists in a 10 two part housing or yoke composed of forged or pressed steel interchangeable halves.

The object of the invention is a light, strong yoke which can be cheaply made, and which can be easily removed and replaced to give access to the parts of the draft gear.

20 Further objects appear in connection with the following description of the draw bar yokes shown in the accompanying drawings, and what the invention consists in is more particularly defined in the appended 25 claims.

In the drawings, wherein the same reference characters are used to designate like parts in the several views, Figure 1 is a 30 plan view of the draft sills and draft gear of a railway car embodying one form of the invention, partly in section on the horizontal axial plane of the draw bar yoke; Fig. 2 is a side view of the same, with a portion of one sill removed to disclose the draw bar yoke; 35 Figs. 3 and 4 are vertical cross-sections on the lines 3—3 and 4—4, respectively, in Fig. 1; Fig. 5 is a plan of a sheet metal blank suitable for producing one of the interchangeable halves of the draw bar yoke 40 shown in Figs. 1 to 4; Fig. 6 is a perspective view of a draw bar yoke comprising halves made from the blank shown in Fig. 5; Fig. 7 is a perspective view of one of the halves of the yoke shown in Fig. 6.

45 The draft gear shown in Figs. 1 to 4, inclusive, is of a tandem spring type, but the invention is applicable to twin-spring, friction, and other types of draft gear. The draft sills 11 are fitted with suitable draft 50 lugs 12 for two sets of follower blocks 13 and springs 14, arranged in tandem between the sills. A metal plate 15 which is bolted to the under sides of the draft sills supports the yoke 16. The yoke 16 is made in top and 55 bottom sections or halves 17 which are counterparts of each other, as shown in Figs. 6

and 7. The sections 17 are forged or pressed from a sheet steel blank shaped as shown in Fig. 5. The blank consists of a straight middle portion having pairs of oppositely disposed wings 18 at each end, each of which wings is punched with a slot 19 parallel to the centerline of the blank. The slots 19 are arranged in pairs on opposite sides of the centerline of the blank, the slots in each pair being equidistant from the center line of the blank. The wings 18 of each pair are bent at right angles to the plane of the blank and parallel to each other, with the slots 19 in alinement, forming side walls at the ends 70 of the yoke. One pair of wings is bent along lines which are wider apart than the lines upon which the other pair are bent so that the wider spaced pair of wings straddle the closer spaced pair of wings of the 75 mating half section 17 in assembled position. Across the middle of each section 17 is an abutment 20 half as high as the side walls 18 formed by bending up the side tongues 21 at right angles to the plane of the blank 80 and bending their extremities across the blank and riveting them together, as shown in Fig. 7. The spaces between the abutments and the inner edges of the side walls 18 at the ends of the yoke members are 85 slightly less than the spaces between the corresponding pairs of draft lugs 12.

The two mating half sections 17 are assembled one inverted above the other, with the wider spaced wings or walls on one section embracing the narrower spaced wings or walls on the other section and the slots 19 at each end of the sections in alinement. The abutments 20 of the two sections meet at their tips and together form a stiff cross 95 wall at the middle of the yoke. The two sections 17 are held together by pins 22 through the alining slots 19 in the side walls. The ends of the sections 17 have narrow flanges 23 turned up between the side walls 100 18. The front end of the yoke incloses the tail end of the draw bar 24, to which it is secured by the front transverse pin 22. The tail end of the draw bar has a pair of oppositely disposed shoulders 25 which fit inside 105 of the flanges 23 and assist in transmitting the pull on the drawbar to the yoke. The extremity of the draw bar bears against the forward follower block 13.

The pins 22 pass through the yoke from 110 side to side, and the ends of the pins pass through slots 26 in the draft sills and are se-

cured in place by cotter pins 27 through their projecting extremities outside of the side walls 18. The slots 26 in the draft sills are considerably longer than the width of 5 the pins 22 in order to permit the latter to have as much movement lengthwise of the car as the draw bar and yoke. The yoke shown in Figs. 1 to 7 may be easily detached from the draw bar by merely taking out the 10 forward pin 19 and lifting the top section sufficiently to disengage the flanges 23 and shoulders 25.

The webs form the side walls of the yoke and have two openings 32 spaced lengthwise 15 thereof, through which the followers are arranged. These openings are separated by intermediate portions 33 of the web which form a middle abutment for the middle followers. The forward end of the web or side 20 wall of each section is punched with a narrow slot 34. The slots of the two half sections are in alinement and the pin which secures the draw bar in place passes through them. The top and bottom flanges of the 25 side sections are provided at their front ends with inturned cross flanges 35 which engage with the shoulders of the draw bar to take the draw bar pull. The rear ends of the sections 31 are closed by semi-cylindrical flanges which connect the rear ends 30 of the top and bottom flanges. The two sections 31 are held together by the transverse pin which secures the draw bar. Cotter pins may be passed through the ends of this 35 draw bar pin to keep it in position in the slots 34.

The two sections of the yoke member are arranged parallel to each other and the draft springs are compressed and with the 40 followers are assembled in the space within the yoke with the followers projecting through the opening in the side walls. The assembled yoke members and draft gear are placed between the draft sills, with the 45 front ends of the sections separated enough to permit the tail end of the draw bar to be slipped endwise between the end flanges of the sections, whereupon the latter are brought together and the assembled parts 50 are secured in place between the draft sills by passing the pins 22 through the sills and yoke sections.

The invention is not restricted to the forms and arrangements of the parts as shown and described.

I claim the following as my invention:

1. A pressed steel draw bar yoke member having side walls and openings therein for the draft gear followers, and an abutment for said followers comprising integral portions of the side walls bent across the centerline of the yoke and secured to the opposite side wall. 60

2. A pressed steel draw bar yoke member having side walls and openings therein for the draft gear followers, and an abutment for said followers comprising integral portions of the side walls bent across the centerline of the yoke and secured to the opposite side wall, said bent portions being approximately one-half the height of the side walls at the ends of the yoke and adapted to abut against the like bent portions of an inverted counterpart yoke member assembled therewith. 70

3. A pressed steel draw bar yoke member having side walls at its ends, the side walls at one end being spaced farther apart than the side walls at the other end, and slots through said side walls at the same distance from the bottom wall of said yoke member, whereby said yoke member may be inverted over a similar yoke member with the side walls at the ends of said yoke members embracing each other, and with said 80 slots in alinement at each end. 75

4. A pressed steel draw bar yoke composed of duplicate counterpart halves which are coextensive in length and width and which are interlocked and secured together 90 and to the draw bar by duplicate transverse pins.

5. A pressed steel draw bar yoke composed of duplicate counterpart halves which are coextensive in length and width and 95 which are interlocked and secured together and to the draw bar by transverse pins adapted to pass through the draft sills, one of said pins being removable to permit removal of the draw bar without removing 100 said draw bar yoke.

Signed at Pittsburgh Penna this 2nd day of July, 1915.

WILLIAM D. FORSYTH.
